UNITED STATES PATENT OFFICE

161,083

HAT DISPLAY STAND

Sol Bernstein, New York, N. Y., assignor to Miller Bros. Hat Co., Inc., New York, N. Y., a corporation of New York

Application March 2, 1950, Serial No. 8,289

Term of patent 14 years

(Cl. D80—9)

To all whom it may concern:

Be it known that I, Sol Bernstein, a citizen of the United States of America, resident of New York city, in the county of Bronx and State of New York, have invented a new, original, and ornamental Design for a Hat Display Stand, of which the following is a specification, reference being had to the accompanying drawing, forming part thereof.

Fig. 1 is a front perspective view of a hat display stand, showing my new design; and

Fig. 2 is a side view thereof.

I claim:

The ornamental design for a hat display stand, substantially as shown.

SOL BERNSTEIN.
